[57] CLAIM

The ornamented design for a exfolient and epidermabrasion pad, as shown and described.

DESCRIPTION

FIG. 1 is a view in perspective of an exfolient and epidermabrasion pad as seen from the top, side, and one end showing our new design;

FIG. 2 is a view in top plan thereof;

FIG. 3 is a view in bottom plan thereof;

FIG. 4 is a view in side elevation, the side opposite that shown being a mirror image thereof; and

FIG. 5 is a view in end elevation, the end opposite that shown being a mirror image thereof.
